Primary Examiner — Cynthia Underwood(74) *Attorney, Agent, or Firm* — Perkins Coie LLP(57) **CLAIM**

The ornamental design for an exhaust fan recapture generator, as shown and described.

DESCRIPTION

FIG. 1 is a front perspective view of an exhaust fan recapture generator.

The side perspective and back perspective views of the exhaust fan recapture generator appear the same as FIG. 1. FIG. 2 is a top view of the exhaust fan recapture generator; and,

FIG. 3 is a bottom view of the exhaust fan recapture generator.

The broken lines represent portions of the structure that form no part of the claim.
